UNITED STATES PATENT OFFICE.

ALFRED W. RASMUSSEN, OF CHICAGO, ILLINOIS, ASSIGNOR TO ERIK L. KRAM, OF SAME PLACE.

TEMPORARY BINDER.

SPECIFICATION forming part of Letters Patent No. 623,627, dated April 25, 1899.

Application filed April 13, 1898. Serial No. 677,410. (No model.)

To all whom it may concern:

Be it known that I, ALFRED W. RASMUSSEN, a citizen of the United States, residing at Chicago, in the county of Cook and State of Illinois, have invented a new and useful Improvement in Temporary Binders, of which the following is a specification.

My invention relates to an improvement in temporary binders for use in holding loose leaves, ledger-sheets, bills, orders, or the like.

My object is to provide a binder of this nature having readily-separable covers provided with means for locking them automatically and firmly together.

The invention consists in two separable covers, the lower one of which is provided at its rear margin with upwardly-extending posts and the other at its rear margin with perforations to receive said posts, and a locking device for the parts comprising sheet spring-metal strips preferably bent upon themselves and each secured at one end to the perforated cover-section and provided with perforations normally slightly out of registration with the cover-section perforations.

In the accompanying drawings, Figure 1 is a plan view of the upper cover-section equipped with my improved spring locking device; Fig. 2, a view in rear elevation of the binder, showing the cover-sections separated somewhat; and Fig. 3, a broken sectional view taken on line 3 of Fig. 1.

A is the top cover-section, and B the lower cover-section, the sections being provided by preference with metallic binding-strips A' B', hinged to the sections by canvas hinges t. The strip B' is provided with upwardly-projecting posts B², which extend through perforations in the binding-strip A' of the upper cover-section.

Attached to the strip A' of the upper cover-section are spring-metal locking-strips C and D. These strips are preferably of the U shape shown, being composed of lower members r and upper members r'. The ends of the springs project outwardly, and the ends of the lower members are secured by means of rivets r² to a common securing member E, which in turn is secured to the strip A' of the top cover member by means of rivets q. This

is the preferred construction; but the springs may be rigidly connected together in a manner to permit them to perform their locking function by fastening them directly to the 55 cover-section or to the strip E simply. The lower members are provided each with a perforation which registers accurately with the corresponding perforation in the strip A', while the upper members are provided with 60 elongated openings p, which in the normal position of the springs are slightly out of registration with the lower perforations, so that the upper members of the springs have frictional contact with the posts at the inner 65 ends of the elongated openings. The posts may be provided near their tops with notches n to prevent possibility of the parts separating when the covers are full.

The operation of the device is simple and 70 effective. The leaves to be bound are provided with perforations to permit them to be slipped onto the posts B², and after the leaves are in place the cover-section A is pressed down upon them. The frictional contact of 75 the upper spring members with the posts causes the outer ends to rise relatively to the lower members as the cover-section is pressed down, thereby causing the grip of the springs to become lessened till the upper members 80 slip readily along the posts. When it is attempted to raise the cover-section, however, the friction causes the springs to coil farther inward, thereby increasing the gripping action as the force applied is increased. To release the cover-section, it is necessary first to 85 raise the ends of the springs, thereby to bring the elongated openings more correctly into registration with the lower openings, when the removal is readily effected. 90

Slight modifications in details within the spirit of my invention may be made. For instance, the lower members r of the springs, which are by preference shorter than the upper members, so as to be concealed thereby, 95 may be still further shortened, so as to render unnecessary the post-receiving perforations with which they are here shown provided. An obvious change also would be to transfer the gripping-surface of the springs 100 to the outer ends of the slots, in which case the members r' would preferably be given a

slight downward slant. In such case the **U** shape of the spring could be departed from. In any case the gripping member must be raised slightly above the cover-section to permit a downward "give," which will increase the gripping action when it is attempted to raise the cover-section without first releasing the springs.

What I claim as new, and desire to secure 10 by Letters Patent, is—

1. In a loose-leaf binder, the combination of a lower cover-section provided at its rear margin with upwardly-projecting posts, an upper cover-section provided at its rear margin with post-receiving perforations, and **U**-shaped springs having their lower members secured to the upper cover-section and their upper members provided with slots and in frictional engagement with the posts at such 20 ends of the slots as to allow the cover-section to be readily pressed downward, but to

prevent a reverse movement except by first releasing the springs, substantially as and for the purpose set forth.

2. In a loose-leaf binder, the combination 25 of a lower cover-section provided at its rear margin with posts, an upper cover-section provided with post-receiving perforations, and **U**-shaped springs having their lower members secured to the upper cover-section, and their 30 upper members provided with slots, said upper members being in frictional contact with their respective posts at the ends of the slots toward the connected ends of the members, thereby permitting a downward movement of 35 the upper cover-section but locking it against return, substantially as described.

ALFRED W. RASMUSSEN.

In presence of—

J. H. LEE,

R. T. SPENCER.
